(57) **CLAIM**

The ornamental design for a power module housing, as shown and described.

DESCRIPTION

FIG. 1 is a top, front and right side perspective view of a power module housing showing our new design;
FIG. 2 is a top, rear and left side perspective view thereof;
FIG. 3 is a bottom, rear and left side perspective view thereof;
FIG. 4 is a front view thereof;
FIG. 5 is a rear view thereof;
FIG. 6 is a left side view thereof;
FIG. 7 is a right side view thereof;
FIG. 8 is a top view thereof; and,
FIG. 9 is a bottom view thereof.

The broken lines in the figures illustrate the portions of the design that form no part of the claimed design.

1 Claim, 7 Drawing Sheets
